UNITED STATES PATENT OFFICE.

WALTER JAMES SYKES, OF SAN FRANCISCO, CALIFORNIA.

RECEPTACLE-COVER-OPERATING MECHANISM.

1,169,207.

Specification of Letters Patent. Patented Jan. 25, 1916.

Application filed November 26, 1913. Serial No. 803,290.

To all whom it may concern:

Be it known that I, WALTER JAMES SYKES, a citizen of the United States, residing at the city and county of San Francisco and 5 State of California, have invented certain new and useful Improvements in Receptacle-Cover-Operating Mechanism, of which the following is a specification.

The present invention relates to receptacle 10 cover operating mechanism and particularly to a type adapted for use in connection with refuse receptacles.

The receptacles now generally in use having the detachable or hinged covers are very 15 unsanitary, in that the cover may become accidentally displaced or may be easily removed by various household pets, such as cats and dogs, and the contents of the receptacle are thus exposed to pollute the atmosphere and to attract vermin and insects, which latter have been proven to be the 20 greatest carriers of infection and disease.

The principal objects of my present invention are to provide a device which will 25 position a receptacle cover on a receptacle so that the same will be prevented from becoming accidentally displaced or removed by animals, such as cats and dogs; one by which the removal or positioning of the 30 cover relative to the receptacle may be accomplished by the operator with little difficulty; and one provided with means for disinfecting the contents of the receptacle at all times, thus overcoming the dangers to 35 health caused by the unsanitary receptacles at present employed.

With the above mentioned and other objects in view, the invention consists in the construction and novel combination of parts 40 hereinafter described, illustrated in the accompanying drawings, and pointed out in the claims hereto appended; it being understood that various changes in the form, proportion, size and minor details of construction, within the scope of the claims, may be resorted to without departing from the spirit or sacrificing any of the advantages 45 of the invention.

Referring more particularly to the drawings, Figure 1 is a front elevation of my improved device with the receptacle in dotted

lines, disclosing the guide means, the movable frame to which is secured the receptacle cover, the operating means for the movable frame, and the disinfecting means 55 carried by the movable frame and communicating with the interior of the receptacle through the cover thereof. Fig. 2 is a rear elevation disclosing the mechanism associated with the foot lever for operating the 60 sliding frame. Fig. 3 is a top plan view disclosing more fully the foot lever and the connections associated therewith. Fig. 4 is a side elevation with the cover in a closed position. Fig. 5 is a view in side elevation 65 disclosing the foot lever depressed and the cover in an elevated position.

Referring more particularly to the drawings, wherein like numerals of reference indicate corresponding parts throughout the 70 several views, 1 designates a suitable base plate preferably semi-circular in form, and to which are secured, in any suitable manner, the lower ends of vertical stanchions 2 connected at their upper ends by a cross bar 75 3. Slidably mounted on the stanchions is a suitable frame consisting of the tubular side members 4 which encircle the stanchions, and which are connected adjacent their upper ends by the supporting member 5 and 80 are also connected adjacent their lower ends by the member 6 which is bent or curved in such manner as to permit the placing of a receptacle 7 between the stanchions 2 and beneath the supporting member 5. 85

The supporting member 5 carries arms 8 to the underside of which are detachably connected, in any suitable manner, the receptacle top or cover 9. The supporting member 5 also carries a bracket 10 to the 90 vertical portion 11 of which is connected, in any suitable manner, a receptacle 12 adapted to contain a disinfectant, and said receptacle is provided with a discharge spout or outlet 13 which extends through a suitable opening 95 in the receptacle cover to admit the disinfectant to drop into the receptacle and disinfect the contents thereof.

The mechanism for operating the sliding frame to raise and lower the cover is constructed in the following manner:—A foot lever 14 is pivoted within its length, as at

15, to a supporting member 16, and is formed at one end with a foot pedal 17, and is provided at its opposite end with a transversely extending curved bearing 18 on 5 which operates a similarly curved bearing 19 positioned at right angles over the bearing 18, and carried by the arm 20 of a bell crank 21 which is pivoted, as at 22, to a supporting member 23. The other arm 24 of the bell 10 crank 21 is pivotally connected by a link 25 with the short arm 26 of a bell crank 27, which is pivotally supported by a supporting member 28, and carried by the long arm 29 of the bell crank 27 is a suitable pin 30 15 which engages under the member 6.

It will be apparent that when a downward pressure is applied to the foot pedal of the lever 14, that the bell cranks 21 and 27 will, through their connections with the lever, be 20 caused to move upwardly and the pin 30 will operate on the underside of the member 6 and raise the frame carrying the receptacle cover, as in Figs. 2 and 5. On the release of pressure on the foot lever, the 25 weight of the frame, receptacle cover and disinfectant container, will cause the frame to lower itself and position the cover over the mouth of the receptacle. It will be apparent that the cover when positioned on the 30 receptacle, cannot be accidentally displaced or removed by animals, but may be only removed by a downward pressure on the foot lever. It will also be apparent that on pressure being released on the foot lever, the 35 cover is automatically positioned over the receptacle, and the flanges of the cover when positioned over the receptacle, prevent the removal of the receptacle from under the cover until the same has been slightly raised.

40 Having thus described my invention what I claim and desire to protect by Letters Patent is:—

1. A closure for garbage receptacles and the like, and operating means therefor, comprising a cover, movable supports for the cover between which a garbage receptacle may be placed, connecting means for the supports extending laterally therefrom to pass around the receptacle space, and pivoted means having a part adapted to ride against said connecting means to effect the raising and lowering of the cover supports to correspondingly position the cover, substantially as described.

55 2. In a cover controlling means, the combination with a guiding means adjacent which the receptacle is adapted to be positioned, a sliding member associated with said guiding means adapted to carry the 60 receptacle cover, a foot operated lever, and a link connection between said lever and cover carrying means whereby a movement of the foot operated lever raises or lowers the covering member on said guiding means.

3. In a receptacle cover controlling means, 65 the combination with spaced guiding standards adjacent which the receptacle is positioned, a member slidably associated with each of said guiding standards and having a connecting part extending laterally therefrom to pass around the receptacle, means 70 for securing a receptacle cover to said slidably mounted member, a foot operated lever, and means coöperating with said lever, and the laterally extending connecting part of 75 the sliding frame for raising and lowering said cover relative to the receptacle.

4. In a receptacle closure controlling means, a pair of spaced supporting standards 80 projecting from a base plate, between which receptacle is adapted to be positioned a sliding frame mounted on said supporting standards, a connecting bar carried by the sliding frame extending around the receptacle, means for supporting the receptacle 85 cover to the frame, and mechanism carried by the base plate and coöperating with the sliding frame for raising and lowering said frame on said standards to move the cover 90 relative to the receptacle.

5. In a receptacle closure operating means, the combination with spaced supporting standards between which a receptacle is adapted to be positioned, tubular 95 members slidably mounted on said standards, a supporting member connecting said tubular members at their upper portions thereof and to which the receptacle cover is adapted to be attached, a connecting member carried by said tubular members, a foot 100 operated lever, and means associated therewith and coöperating with said connecting member for operating the same on said standards to raise and lower the receptacle 105 cover relative to the receptacle.

6. In a receptacle closure operating means, the combination with spaced supporting standards between which a receptacle is adapted to be positioned, members 110 slidably mounted on said standards, means for attaching a receptacle cover to said sliding members, a connecting arm carried by the sliding members, and means for operating the said sliding member on said standards to raise and lower the receptacle cover 115 relative to the receptacle comprising a foot operated lever having mechanism associated therewith carrying a part adapted to ride against the said connecting member.

7. A receptacle cover controlling means, 120 the combination with a base plate carrying vertically extending guiding standards adjacent which a receptacle is positioned, a sliding member associated with the guiding standards adapted to carry a receptacle 125 cover, a foot operated lever pivotally secured to a supporting member carried by the base plate, a bell crank lever having a part

coöperating with the frame carried by said base plate, and a connection between the foot operated lever and the bell crank lever whereby a movement of the foot lever raises or lowers the cover carrying member or guiding standards.

In testimony whereof I have signed my

name to this specification in the presence of two subscribing witnesses.

WALTER JAMES SYKES.
